KEY CASE

Joseph E. Rom, Detroit, Mich.

Application December 29, 1949, Serial No. 135,761

2 Claims. (Cl. 70—456)

1

This invention relates to an improved key container and selector mechanism of the type comprising a case adapted to hold several keys and to permit any one of the latter to be selectively swung from the case to an operative or useful position.

An important object of the present invention is to provide an improved simplified key container and selector mechanism of the foregoing character comprising a plurality of parallel plates arranged in superimposed relation and adapted to contain one or more keys in swinging relation between the plates, whereby the keys may be swung outward from between the plates to the operative position, the keys being selectively retained between the plates by one or more sliding members adapted to slide along edge portions of the plates to and from positions blocking the outward swinging of the keys.

Other objects are to provide such a mechanism whereby the parallel plates are maintained in spaced relation by pivot members upon which the keys are detachably mounted for the aforesaid swinging relation, and whereby the sliding members engage the edge portions of the outer plates in sliding relation to prevent separation thereof, the sliding members being detachable from the plates in a preferred construction to permit separation of the plates and replacement of keys therebetween.

Another and more specific object of the present invention is to provide a laminated key case of the foregoing nature comprising three parallel plates adapted to contain two keys in swinging relation between each of the two pairs of plates, the keys being pivotal about axes spaced longitudinally of the case for swinging the operating portions of the keys between each pair of plates inward in lapping relation from opposed lateral edges of the case, or laterally outward in opposite directions to said operating positions, a sliding selector member being provided to slide along each of the opposed lateral edges of the case to and from positions blocking the outward swinging of the keys.

In a preferred construction, each of the longitudinally spaced pivot axes for the keys between each pair of plates is coaxial with one of each of the pivot axes for the keys between the other pair of plates, and a stop is located intermediate the spaced pivot axes to limit inward swinging of the keys. Preferably in this construction, the keys of each coaxially swinging pair are arranged to swing inward into engagement with their respective stops from opposed lateral edges

2

of the case. Thus two of the four keys may be swung laterally outward from one lateral edge of the case, one key being swingable about one longitudinally spaced axis from between one pair of plates and the other key being swingable about the other axis from between the other pair of plates. The remaining two keys of course are similarly arranged for swinging outward from the other lateral edge of the case.

10 The case is adapted so that either sliding member may be slid in either direction longitudinally of the case along the corresponding lateral edge, so as to free one key for outward swinging about its axis, but not to free the other key. Accordingly, by properly adjusting the sliding members, all of the keys may be retained within the case, or any one of the four keys may be selectively freed for outward swinging to the operative position. In order to facilitate orientation and use 15 of the case in the dark, an end of one outer plate is preferably knurled or suitably marked to permit identification by touch.

Other objects of this invention will appear in the following description and appended claims, 20 reference being had to the accompanying drawings forming a part of this specification wherein like reference characters designate corresponding parts in the several views.

Details of a preferred construction and application of the present invention are illustrated in 25 the drawings wherein:

Fig. 1 is an enlarged plan view of a key case embodying the present invention.

Fig. 2 is a longitudinal mid-section taken in the direction of the arrows substantially along 30 the line 2—2 of Fig. 1.

Fig. 3 is an exploded view showing the component parts of the key case in side elevation with the keys removed.

40 Fig. 4 is a fragmentary enlarged transverse section taken in the direction of the arrows substantially along the line 4—4 of Fig. 1.

Fig. 5 is a section taken in the direction of the arrows substantially along the line 5—5 of Fig. 2, 45 showing a preferred arrangement of the keys between one pair of the key case plates.

Fig. 6 is a section taken in the direction of the arrows substantially along the line 6—6 of Fig. 2, showing a preferred arrangement of the keys between the other pair of plates.

50 It is to be understood that the invention is not limited in its application to the details of construction and arrangement of parts illustrated in the accompanying drawings, since the invention is capable of other embodiments and of

being practiced or carried out in various ways. Also it is to be understood that the phraseology or terminology employed herein is for the purpose of description and not of limitation.

Referring to the drawings, a laminated key case is shown comprising in the present instance three parallel plate members 10, 12 and 14 arranged in spaced superimposed relation with parallel superimposed lateral edges comprising the opposed lateral edges of the case. In the present instance, the plates are maintained in spaced parallel relation by three pairs of interengaging retaining or spacer members spaced along the longitudinal mid-line of the case. Each pair of retaining members includes a cylindrical socket member 16, integral with the outer plate member 14 and extending inward therefrom, and a cylindrical boss 18 integral with the outer plate 10 and extending inward therefrom. Extending coaxially inward from each boss 18 and integral therewith is a pintle 20 of reduced diameter adapted to pass snugly through an aligned opening 22 provided therefor within the middle plate 12 and snugly into the bore of the corresponding cylindrical socket 16, whereby relative parallel movement between the plates is prevented. The socket 16 and boss 18 extend perpendicularly inward from their respective plates 14 and 10 equal distances determined by the desired spacing between the confronting surfaces of the plates and terminate respectively in annular shoulders or abutment surfaces 24 and 26 parallel to the plates and located around the bore of the socket member 16 and the base of the pintle 20 respectively, Fig. 3.

By the construction described thus far, it is apparent that the middle plate 12 rests on the shoulders 26 in parallel spaced relation to the outer plate 10. Similarly the middle plate 12 is maintained in parallel spaced relation with the outer plate 14 by abutment against the shoulders 24.

Separation of the plates perpendicularly from each other is prevented in the present instance by a pair of sliding riders or selector members 28 and 30 extending perpendicularly to the plates, one at each opposed lateral edge of the case, Fig. 4. The two opposed outer ends of each rider 28, 30 are provided with integral V-section inward extensions 32 overlapping and interlocking with adjacent V-section outer edge portions of the plates 10 and 14 in sliding relation. The interior angle between each extension 32 and the body of the corresponding rider 28 or 30 comprises a longitudinally extending groove or slideway 34 of V-section interfitting with the aforesaid adjacent edge portions of the plate 10 or 14, as the case might be. The sectional shape of the latter edge portions results from a V-section groove or slideway 36 interfitting with each extension 32 and provided longitudinally in the lateral outer surface of the appropriate plate 10 or 14. Thus riders 28, 30 are freely slideable along the slideways 36, but are prevented from lateral separation from the case by reason of their interengagement with the edges of the plates 10 and 14. The latter in turn are held against separation by interengagement with the overlapping extensions 32 of the riders 28, 30. For reasons to be made apparent hereinafter, the extent of sliding movement of the riders 28, 30 is limited by termination of the slideways 36 at opposite ends short of the endmost interengaging spacers 16, 18, Fig. 1. As indicated in Figs. 3 and 4, manipulation of the riders 28, 30 is facil-

itated by reason of their knurled lateral surfaces.

The cylindrical socket members 16 and bosses 18 are of substantially equal diameters and are adapted to extend freely through the usual opening provided in the handle portion of a conventional key as illustrated in Figs. 5 and 6. Likewise the spacing between each pair of confronting surfaces of the plates afforded by the members 16, 18 is determined so that a key pivotally mounted on either of these members will swing freely to and from positions between the plates. The key case in the present instance is particularly adapted to contain four keys, as for example the two keys 38 and 40 pivotally mounted on one of each of the two endmost socket members 16 for swinging between the plates 12 and 14 and the two keys 42 and 44 pivotally mounted on one of each of the two endmost cylindrical bosses 18 for swinging between the plates 10 and 12.

Preferably, the keys 38 and 40 are arranged on their respective pivot mountings 16 with their operating portions extending toward each other in lapping relation and spaced by the intermediate socket member 16. Thus when freed for outward swinging by suitably positioning the riders 28 and 30 as described hereinafter, the keys 38 and 40 may be selectively swung laterally outward in opposite directions from each other to useful or operative positions. The keys 42 and 44 are similarly pivotally mounted on their cylindrical bosses 18 for swinging laterally outward in opposite directions from each other, but the operating portions of these keys are preferably separated by the intermediate boss 18 so that outward swinging of the keys 38 and 42 will be in opposite directions. Similarly outward swinging of the keys 40 and 44 will also be in opposite directions from each other. It will be apparent that the specific arrangement of the keys illustrated is not essential, although certain advantages are achieved if each key swings laterally outward from the case oppositely to both the companion key mounted between the same two plates and the key coaxially mounted between the other two plates. Many advantages of the present invention will be obtained using more or less than two riders, or more or less than three parallel plates. Likewise the preferred rectangular plan of the case may be modified where desired without departing from the spirit of the invention.

It is apparent from the foregoing that when the riders or selectors 28 and 30 are located at positions approximately intermediate the pivot axes for the keys, i. e. substantially opposite the central spacer 16, 18, all of the keys will be retained within the case against outward swinging. Upon sliding the selector 28, as for example leftward as illustrated, to the limit of longitudinal movement permitted by the slideways 36, the key 44 is freed to swing outward from between the plates 10 and 12 to an operative position. The keys 40 and 42 will of course be retained between the rider 30 and the corresponding members 16 and 18. The key 38 is prevented by abutment with the rider or selector 28 from swinging to an operative position even though a limited outward swinging of that key might be possible.

The other keys may similarly be selectively located by moving the riders 28, 30 to other positions. For example the key 38 will be released for outward swinging upon moving the rider 28 to the right beyond the swinging end of

the key 38. The keys 40 and 42 will be freed for outward swinging upon movement of the rider 30 to the left or right respectively beyond the swinging ends of these latter keys.

It is to be observed in this connection that the length of the sideways 36 is determined so that the selectors 28 and 30 may be moved in either direction beyond the tip of the swinging end of the key to be released, but not beyond either of the endmost spacer members 16, 18. Likewise, the longitudinal spacing between the endmost pivot members 16, 18 is somewhat greater than the swinging radius arm afforded by any key for which the case is adapted, but is less than twice the smallest contemplated radius arm. Thus the middle spacer 16, 18 will serve as a stop for inward swinging of the keys, but the swinging end of the selected key will swing outward clear of the corresponding rider 28 or 30 when the latter is at the limit of its longitudinal movement in a direction away from the pivot axis of the selected key.

The parallel plates 10, 12, 14 may be formed of any lightweight sheet material of suitable rigidity, as for example a thermoplastic or thermosetting plastic material, and are preferably sufficiently resilient to permit the superimposed lateral edges of either side of the case to be sprung toward each other sufficiently to disengage the riders 28 and 30 from their guideways 36. Thus the case may be readily disassembled and reassembled to permit the addition or removal of the keys.

In order to facilitate orientation of the key case in the dark by touch, the outer surface of one plate at one end is suitably scored or knurled, as for example in the manner of the parallel knurlings 46 in the left outer surface of the plate 14, Fig. 1. Such a marking will suffice for properly orientating the case, although the plates may be suitably numbered or lettered adjacent the pivot axis for each key if desired.

I claim:

1. In a key holder, a laminated case comprising three plates adapted to contain a pair of keys between each adjacent pair of plates in

swinging relation, a pair of pivot means spacing the plates at locations spaced longitudinally of the case and being adapted to pierce the handle elements of the keys to hold the same in said swinging relation for swinging the keys laterally from between the plates to operative positions, and means engaging the outer plates to prevent separation thereof, the last means including a pair of slide members slidable along laterally opposed edges of the case to and from positions blocking lateral swinging of the keys to said operative positions.

2. In a key holder, a laminated case comprising three plates adapted to contain a pair of keys between each adjacent pair of plates in swinging relation, a pair of pivot means spacing the plates at locations spaced longitudinally of the case and being adapted to pierce the handle elements of the keys to hold the same in said swinging relation for swinging the keys laterally from between the plates to operative positions, movement limiting means intermediate said pair of pivot means to limit inward swinging of each key, and means detachably engaging the outer plates to prevent separation thereof, the last means including a pair of slide members slidable along laterally opposed edges of the case to and from positions blocking lateral swinging of the keys to said operative positions.
